UNITED STATES PATENT OFFICE.

MILES E. HOUSEHOLDER, OF PITTSBURGH, PENNSYLVANIA, ASSIGNOR TO THE DURALECTRIC CORPORATION, OF PITTSBURGH, PENNSYLVANIA.

ELECTRIC HEATER.

Application filed October 29, 1921. Serial No. 511,246.

To all whom it may concern:

Be it known that I, MILES E. HOUSEHOLDER, a citizen of the United States of America, residing at Pittsburgh, in the county of Allegheny and State of Pennsylvania, have invented certain new and useful Improvements in Electric Heaters, of which the following is a specification.

My invention relates to improvements in 10 electric heaters for heating water and other liquids.

An object of my invention is the construction of a heater in which the elements of the heating unit are not easily broken; in which 15 the elements, if broken, may be readily replaced with very little expense; in which several of the elements are duplicates, thus providing for economical repair; and in which the elements are all held together by 20 a single binding means.

A further object of my invention is the construction of a device in a manner to prevent the feed wires from being injured by the intense heat developed in the heating 25 unit, and in which the connections of the feed wires are outside of and removed from the heating unit.

A still further object is the use of means to prevent any moisture which collects on 30 the inner copper tube from reaching and injuriously affecting the electric contacts.

A still further object is the use of means to prevent the resistance wires from coming 35 in contact with the copper tubing near which they are placed.

As a means of increasing the efficiency of my device, I place a very thin metal tube between the resistance wires and the water, and I also provide a narrow water space between 40 the metal tube and the outside casing. In this way the desirable objects of rapid and economical heating are accomplished.

A still further object is to prevent arcing 45 of the resistance wires at the points of connection.

A form of my device is illustrated in the accompanying drawings, in which:

Figure 1 is a longitudinal section of my heater;

Figure 2 is a section on the line 2—2 of Figure 1;

Figure 3 is a section on the line 3—3 of Figure 1;

Figure 4 is a section on the line 4—4 of Figure 1; 55

Figure 5 is a perspective of the junction box; and

Figure 6 is a detail view showing the locking means of the upper ends of the coils.

My heater comprises a casing 1, the upper end of which has screw-threaded therein a reducer 2 through which the heated water passes. Screw-threaded to the lower end of the casing is a T 3 having a water inlet 4. Within the casing is a metal tube 5 which 60 may be brazed shut at the top by a copper disc 6. The lower end of the tube is open for the insertion of the heating elements, and brazed to the outside thereof is a screw-threaded bushing 7 for connection with the 65 T 3. 70

The heating unit consists of any desired number of resistance coils 8, six being shown, all of which are secured to a porcelain top disc 9 in any suitable manner, as by screws 75 10. In order to prevent the arcing of the wires at the points of connection on the top of the disc, the ends of each pair of wires are locked between two brass washers 10^a and 10^b, and a brass nut 10^c; the latter being 80 screw-threaded on the screw 10. A nut 10^d below the disc 10 holds the screw 10 in place. By the use of the washer and the nut 10^c the connections are firmly maintained even if the disc 9 should shrink materially. The 85

coils are kept in position and prevented from coming in contact with the copper tube 5 by porcelain discs 11, two of which are shown; but it is understood that the heating unit may have as many of these discs as desired, 90 depending, of course, on the length of the heater. Towards the bottom of the tube and opposite the inlet 4 is a porcelain disc 12, through which the ends of the coils extend and from which they are carried through a 95 space in the tube 5 to an asbestos plate 13 at the bottom of the tube, through which they pass and on the bottom of which they are connected to feed wires 14 by any suitable means, as by contact screws 15. The discs 100 11 are separated from each other and from the end discs by porcelain tubes 16. Be-

tween the bushing 7 and the asbestos plate 13 is placed a metal drainage plate 17 having an upturned flange for the purpose of collecting any moisture which condenses and 5 runs down the inside of the copper tube 5. All the parts of the heating unit are connected by a rod 18 having nuts 19 and 19^a on the ends thereof. The junction box 20 has an opening 21 for the feed wires, and 10 may have a removable bottom 22 attached by screws 23 entering flanges on the bottom of the box. This box has ears 24 by which it is attached to the bushing 7 in any suitable way, as by screws 25. The flanges 26 of 15 the box are attached to the bottom of the asbestos plate 13 by screws 27. An asbestos pad 28 may be suitably placed in the junction box as an added protection for the feed wires against the heat which develops in the 20 heating unit.

It will be apparent that all the parts of the heating unit may be taken out and any of the parts replaced without shutting off the water.

25 While my heater is adapted to be used as a hot water heater, it may be attached to a hot water radiator.

By the use of a thin inner tube to confine the heating unit, and by having a narrow 30 water space, the heating of water is rapidly and economically effected.

The heater may be wired to act on two, four, or six coils, in a manner well known in the electrical art.

35 It will be noted that I have provided a space between the coils and the contact ends of the coils and have placed an asbestos disc at the lower end of this space, thus remedying the defect of subjecting the ends of the 40 feed wires to excessive heat.

It will be noted that the junction box holds the heating unit in place as a result of its attachment to the bushing around the copper tube and the attachment of the asbestos plate at the bottom of the copper tube to the flange of the junction box.

45 It will be understood that the discs referred to herein as being made of porcelain may be made of other suitable material, and 50 that the pads referred to herein as being made of asbestos may be made of other suitable material without departing from the spirit of my invention.

Having described my invention, what I 55 claim is:

1. An electric water heater comprising a casing and a removable heating unit located in said casing, said unit comprising a tube, resistance coils in said tube, and means 60 to prevent said coils coming in contact with each other and with said tube, said means comprising a plurality of discs.

2. An electric water heater comprising a casing and a removable heating unit located

in said casing, said unit comprising a tube, 65 resistance coils in said tube, and means to prevent said coils coming in contact with each other and with said tube, said means consisting of porcelain discs.

3. An electric water heater comprising a 70 casing and a removable heating unit located in said casing, said unit comprising a tube, resistance coils in said tube, one end of each of said coils continuing a distance through the tube before being connected to a feed 75 wire, and means to prevent said coils coming in contact with each other and with said tube, said means consisting of porcelain discs.

4. In an electric water heater, a heating 80 unit comprising resistance coils and means to prevent the ends of said coils from coming in contact with condensed moisture, said means comprising a flanged plate forming a trough to receive and hold moisture. 85

5. In an electric water heater, a heating unit comprising resistance coils, said coils being disconnected from each other in said unit, discs to space said coils apart, supports for said discs, and means to attach all 90 parts together.

6. In an electric water heater, a heating unit, a junction box located beneath, said unit, feed wires in said junction box, and a heat resisting plate in said junction box 95 to protect the feed wires from the heating unit.

7. An electric water heater comprising a casing, a tube in said casing, said tube located relatively near to the inside wall of 100 said casing, said tube being of thin metal, and said tube being removably joined to the bottom of said casing, resistance coils in said tube, said coils being disconnected from each other, porcelain discs in said tube to separate said coils from each other and to space 105 said coils from said tube, a porcelain disc located near the top of said tube, said coils being connected to said top disc, an asbestos plate located at the bottom of said tube to 110 close the bottom thereof, a porcelain disc in said tube spaced above said asbestos plate, said plate and said disc forming a space in said tube for the ends of said coils to pass through, a junction box attached to 115 said plate, feed wires in said junction box, contacts for the ends of said feed wires and the ends of said coil wires on the under side of said plate, and an asbestos plate 120 spaced below said contacts, said plate having openings therein for said feed wires.

8. In a device of the kind described resistance coils and means to lock the ends of said coils, said means comprising a disc through which the ends of said coils extend, a locking screw connected to said disc and means on said screw to hold the ends of 125 said coils, said means acting independently

of the connection of the screw with the disc.

9. In a device of the kind described resistance coils and means to lock the ends of said coils, said means comprising a disc 5 through which the ends of said coils extend, a locking screw passing through said disc, a nut on the end of said screw, a washer on

said screw and a nut below said washer adapted to clamp the ends of the coils between said washer and said nut.

10 In testimony whereof I affix my signature.

MILES E. HOUSEHOLDER.
